UNITED STATES PATENT OFFICE.

JAMES EDWARD SMOOT, OF CONCORD, NORTH CAROLINA.

HOLDER FOR PENCILS AND ERASERS.

Application filed January 16, 1920. Serial No. 351,968.

To all whom it may concern:

Be it known that I, JAMES EDWARD SMOOT, a citizen of the United States, residing at Concord, in the county of Cabarrus and 5 State of North Carolina, have invented a new and useful Holder for Pencils and Erasers, of which the following is a specification.

It is the object of this invention to provide a simple device adapted to hold an eraser and a crayon or pencil, the construction being such that short pieces, otherwise wasted, may be rendered useful.

The invention aims to provide, in a device of the class described, an ejector of novel construction, cooperating in a novel way with the sleeve which holds the eraser and the pencil.

It is within the province of the disclosure 20 to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that, within the scope of what is claimed, changes in 30 the precise embodiment of the invention shown can be made without departing from the spirit of the invention.

In the accompanying drawings:—

Figure 1 shows in side elevation, a device constructed in accordance with the invention; Figure 2 is a cross section taken approximately on the line 2—2 of Figure 1; Figure 3 is a cross section taken approximately on the line 3—3 of Figure 1; and 40 Figure 4 is an elevation disclosing the opposite side of the device from that depicted in Figure 1, the pencil and the eraser having been omitted.

In carrying out the present invention, 45 there is provided a sleeve 1, preferably made of resilient metal, the sleeve being provided with a slot 2, extended from one end of the sleeve to the other. The sleeve 1 is supplied at its ends with beads 3. An ejector is mounted for reciprocation on the sleeve 1, longitudinally thereof, the ejector being fashioned from a single strip of resilient metal disposed in annular form, the strip being bent intermediate its ends to 50 form an inwardly projecting double walled finger 5 movable in the slot 2 of the sleeve

1 and projecting within the sleeve, the ejector being denoted generally by the numeral 4. The ejector includes free terminals 6, which bear upon the sleeve 1 at a point diametrically opposite to the slot 2.

A pencil or crayon 8 is inserted in one end of the sleeve 1 and an eraser 7 is inserted in the other end of the sleeve. The ejector 4 may be slid into cooperating relation with the eraser 7 or into cooperating relation with the pencil 8, to advance or eject either the eraser or the pencil, the ejector exercising its function when the finger portion 5 thereof comes into contact with the inner end of the eraser or with the inner end of the pencil.

There is an advantage in providing the ejector 4 with the finger 5, located midway between the ends 6 of the ejector. Owing to this construction, the free ends 6 of the ejector engage with the sleeve 1 at a point diametrically opposite to the slot 2. The sleeve, therefore, is not likely to open, and loosen its hold on the eraser or the pencil. The ejector 4 grips the sleeve 1 with a close sliding fit, but the ejector may be advanced toward either end of the sleeve 1, if pressure is applied to the ejector. The beads 3 serve to prevent the ejector 4 from being slid completely off the sleeve 1.

Since the sleeve 1 is resilient, it may be spread sufficiently to accommodate pencils and erasers of different diameters, the ejector 4 expanding as the sleeve expands and contracting as the sleeve contracts. The construction is such that a sure grip upon the pencil and the eraser may be had, and short pieces which otherwise would be cast away, may be rendered useful. The ejector 4 may be used or omitted as occasion may demand, but when it forms a part of the device, the structure will include a simple but efficient means whereby the pencil or the eraser may be advanced or be removed from the sleeve. Especial attention is directed to the fact that the finger 5 of the ejector 4 is of double-walled construction. Owing to this feature, the finger of the ejector will be unusually stiff and will be strong enough to advance either the eraser or the pencil, should either of these elements be held with a strong frictional grip in the sleeve 1.

Having thus described the invention, what is claimed is:—

A device of the class described comprising a tubular sleeve having a single longi-

23
tudinal slot extended the full length of the sleeve through both ends of the sleeve, the provision of a single slot serving to increase the strength of the sleeve and reducing the 5 number of edges which might fray a garment pocket; and an ejector slideable on the sleeve, the ejector being fashioned from a single strip of material disposed in annular form, the strip being provided with an 10 inwardly projecting finger movable in the slot and extending into the sleeve, the strip having free terminals which extend trans-

versely of the sleeve into end contact at a point diametrically opposite to the slot, thereby to restrain the sleeve from spreading at the slot and to reduce the number of edges which might fray a garment pocket. 15

In testimony that I claim the foregoing as my own, I have hereto affixed my signature in the presence of two witnesses.

JAMES EDWARD SMOOT.
